UNITED STATES PATENT OFFICE.

HARRY D. BLACK, OF WILMINGTON, DELAWARE.

SHUTTER-LOCK.

No. 889,749.

Specification of Letters Patent.

Patented June 2, 1908.

Application filed August 31, 1907. Serial No. 390,894.

To all whom it may concern:

Be it known that I, HARRY D. BLACK, a citizen of the United States, residing at Wilmington, in the county of Newcastle and State of Delaware, have invented a new and useful Improvement in a Shutter-Lock, of which the following is a specification.

This invention relates to a lock for locking outside window shutters in open position and the object of the invention is a lock of this kind which will automatically lock the shutter in an open position when swung back against the side of a building, and which can be released or unfastened from within the building.

The invention consists of a keeper carried by the side of the house and of a spring pressed locking bolt carried transversely by the shutter and projecting therefrom at each end.

In the accompanying drawings, Figure 1 is a perspective view showing my device applied to a building, the shutter being in closed position. Fig. 2 is a side elevation of parts shown in Fig. 1, a portion of the shutter being shown in section. Fig. 3 is a transverse sectional view, the shutter being shown locked in open position. Fig. 4 is a detail perspective view showing a modified form of keeper.

In applying my invention, I take an ordinary shutter A and recess the same upon its inner or hinged edge as shown at A' and also recess its outer face adjacent its opposite edge as shown at A² and connect these recesses by a transverse horizontal passage A³. Through the passage A³ works an operating rod C which passes through the recess A' and projects therefrom, the projecting portion being enlarged to form a push button C'. Around the rod and within the recess A' is a coil spring C². The rod also projects into the recess A², said projecting portion being

threaded, and upon this portion is threaded an angle bolt C³ which is consequently adjustable along the rod and which engages a keeper B secured to the side of the house when the blind is swung back. I have also shown a modified form of keeper adapted for use with stone or brick houses and which consists of a keeper D provided with a barbed shank D'.

The spring C² will normally hold the rod C in the position shown in Fig. 2 and when the bolt is to be disengaged from the keeper, it is not necessary to pass around to the side of the house, as the bolt can be disengaged by pressure upon the push button C'.

Having thus fully described my invention, what I claim as new and desire to secure by Letters Patent, is,

1. The combination with a swinging shutter and a keeper arranged adjacent said shutter, a rod carried transversely by the shutter and movable longitudinally, and an angle bolt adjustably mounted upon an end portion of said rod for engagement with the keeper.

2. The combination with a window shutter recessed upon its hinged edge and upon its outer face and having a passage connecting the recesses, a rod passing through and movable in said passage, and projecting from the edge recess, a spring in said recess for holding said rod in its normal position and an angle bolt carried by the rod and projecting from one side of the rod into the other recess, and a keeper secured adjacent to said shutter and adapted to enter the last mentioned recess when the shutter is swung open and to be engaged by said bolt.

HARRY D. BLACK.
